UNITED STATES PATENT OFFICE.

PATRICK J. FINNERAN, OF BOSTON, MASSACHUSETTS.

DESIGN FOR A SOLE FOR FOOTWEAR.

52,565.

Specification for Design.

Patented Oct. 15, 1918.

Application filed April 8, 1916. Serial No. 90,004. Term of patent 14 years.

To all whom it may concern:

Be it known that I, PATRICK J. FINNERAN, a citizen of the United States, residing at Boston, in the county of Suffolk and State of Massachusetts, have invented a new, original, and ornamental Design for a Sole for Footwear, of which the following is a specification, references being had to the accompanying drawing, forming part thereof.

In the drawings:

Figure 1 is a plan of the tread side of the sole;

Fig. 2 is a longitudinal sectional view; and

Fig. 3 is a transverse section.

What I claim is:

The ornamental design for a sole for footwear, as shown.

PATRICK J. FINNERAN.
